[57] CLAIM

The ornamental design for a wheeled leaf rake, as shown and described.

DESCRIPTION

FIG. 1 is a front view of a wheeled leaf rake, showing my new design;

FIG. 2 is a rear view thereof;

FIG. 3 is a top view thereof;

FIG. 4 is a front view thereof; and,

FIG. 5 is a side view thereof, the unshown opposite side view being of mirror-image appearance.

The handle portion is shown broken-away to indicate indeterminate length.
